UNITED STATES PATENT OFFICE.

MARTIN KARL LEWERENZ, OF ST. CATHARINES, ONTARIO, CANADA, ASSIGNOR TO
LORD & BURNHAM COMPANY, OF IRVINGTON, NEW YORK, A CORPORATION OF
NEW YORK.

GREENHOUSE.

Application filed November 18, 1925. Serial No. 69,733.

This invention relates to improvements in structural members and fittings, but is especially directed to a combined eave-plate and condensation gutter adapted for use in connection with greenhouses and similar structures.

Heretofore in the construction of horticultural buildings, such as greenhouses, it has been the practice to connect the vertical posts to the rafters by means of gusset plates and at the junction of the side wall and the roof introduce an eave-plate adapted to support the edge of said roof. Such an eave-plate is shown in patent to Burnham, No. 583,247, of May 15, 1897, in which the eave-plate is in the form of an angle-iron, one leg of which extends into the interior of the building so as to receive the heat thereof and to act as a conductor of such heat to the part outside the building and prevent the formation of ice and the accumulation of snow. Further, in order to remove the condensation which forms on the inside of the roof, a separate element in the form of a trough or gutter was positioned adjacent to the junction of said side wall and roof and supported by a bracket on either side of said gusset plate. One form of such gutter was a U-bar extending under the edge of the inwardly extending angle-iron above referred to.

The present invention comprehends the provision of a combined eave-plate and condensation gutter, integrally formed, and adapted to perform the usual functions of the eave-plate of the Burnham type with a U-bar gutter, said unitary structure possessing greater strength and rigidity than the separate elements as combined in the present-day structures.

Heretofore it also has been the practice to support the roof bars, or sash bars, as they are sometimes called, in a clasp, the clasp being secured to the eave-plate by bolts passing through the flange of the clasp and the sash-bars held in place in a pocket formed for it in the clasp by one or more screws. It is a well known fact that when two members are brought into close relation to each other, there is a tendency to oxidize, whether the material be of metal or wood. It is a further object of this invention to eliminate these clasps and to provide means for spac-

ing the ends of the roof bars away from the side of the gutter, thereby eliminating the tendency to oxidize or rot.

A further object is to reduce the number of parts by forming the splice plates not only to join the posts and rafters, but also to support the eave-plate and gutter, thus reducing the number of holes to be punched for bolts, as well as effecting a saving in the amount of material used.

Still further objects and advantages will be revealed as the description proceeds, and in order that the same may be better understood, reference is had to the accompanying drawings forming a part of this specification.

In said drawings:

Figure 1 is a sectional view through a portion of the building as viewed from the section line 1—1 of Fig. 2;

Figure 2 is a transverse sectional view taken substantially on the line 2—2 of Figure 1;

Figure 3 illustrates the connection between my improved eave-plate and gutter and the roof-bars lying between rafters as viewed from the section line 3—3 of Figure 4;

Figure 4 is a sectional view taken on the line 4—4 of Figure 3;

Figure 5 is a view like unto Figure 1, but illustrating a modification; and

Figure 6 is a sectional detail view on the line 6—6 of Figure 1.

Referring now in detail to Figure 1 of the drawings, numeral 10 denotes one of a series of vertically disposed posts, which carry a series of rafters 11 through the medium of gusset plates 12. As observed in Figure 2, I employ two splice or gusset plates 12, between which said posts and rafters are secured by means of rivets or bolts as indicated at 13.

The upper portion of said gussets 12 is provided with a downwardly extending portion 12^a for the purpose of supporting a truss 14, thus adding to the rigidity of the structure.

Considering the gusset plate 12 as shown in Figure 1, it will be noted that the formation thereof is of substantially oblique angular configuration and presents relatively a skeleton structure as compared to the

present-day triangular plates, which obviously in a greenhouse is of utmost importance, since the shadow-casting by my improved gusset is greatly reduced when compared with the triangular plates now in use. Such a construction permits the production of the lightest structures possible consistent with a staunch, enduring greenhouse.

10 Said gusset plate 12 is further provided with a flange 15 extending at right angles to the vertical plane of said plate substantially U-shaped together with a slot formed by projecting lip or keeper 15^a and co-operates 15 with a similar flange formed on the companion plate for supporting my combined eave-plate and gutter, as will presently appear.

As viewed in Figure 1, the preferred form of my combined eave-plate and gutter 16 comprises a rolled, substantially U-shaped, portion 17, one end thereof being bent inwardly, as indicated at 18, serving as a support for the roof-bars intermediate the rafters. The other leg portion is bent outwardly 25 and at right angles to assume a position substantially in the same plane as the plane of the roof, as indicated at 20. The upper face of the portion 20 is provided with a longitudinal rib 21, which abuts the lower edge 30 of the glazing 22 and arrests the downward movement of glass thereof. The roof-bars 23 are bevelled at their ends as at 24, and are secured to the inward extension 18 of the member 16 by means of bolts or screws 35 19, which pass through said extension 18 as clearly shown in the drawings, except that in Figure 1 the roof-bar 23 coinciding with the rafter 11 is longitudinally grooved on its under side as at 23^a to receive a corresponding longitudinal rib on the upper face of the rafter. In order to secure the bar to its place on said rib a metal clip 23^a is provided, shaped as shown in Figure 6, to embrace the bar 23. Said clip is provided with suitable apertures to pass the screws 23^b for uniting 40 said clip to the roof-bar 23. The rafter 11 is provided with a suitable transverse opening 11' to permit the insertion therein of the clip 23^a. The latter is then fixedly secured 45 to the rafter-bar by means of the screws 23^b, thus making a rigid connection of the rafter-bar to the rafter. It will be understood that roof-bars of various depths are used in different greenhouses, and in order to keep 50 the same in their proper plane, more especially those between rafters, I have provided the filler piece or adapter 34 for the shallower roof-bars, these adapters being secured to the support 18 also by the bolts 19.

The gutter portion 17 is provided with apertures 27 at suitable intervals, which permit of the escape of the condensation to the drip-pan 28 and thence to the lead-off 29.

As clearly shown in Figure 2, said drip-pan 28 is provided with a lateral extension

30, threadedly receiving the set-screw 31 for securing said pan to the gusset-plate 12, in co-operation with the lug 30^a. Said pan 28 is further provided with a downwardly disposed lug 32, having a V-shaped groove to 70 receive the upper end of said lead-off 29. The set-screw 33 may also be employed if desired.

The abutting ends of the sections of the combined eave-plate and gutter are secured 75 to each other by splice plates 36 and bolts 37.

In the modification shown in Figure 5, the posts 38 are connected to the rafters 39 by means of gusset plates 40. In this instance, the combined eave-plate and gutter is 80 secured to brackets 41, having flanges 41^a corresponding to flanges 15 of Figure 1, by means of bolts 42. In this modification the gutter portion is formed slightly different from my preferred form, there being a downwardly extending right-angled portion 43 connected to the eave-plate proper and an upwardly extending right-angled portion 44 connected to the last named portion, forming a channel therebetween and providing a seat 90 45 for the roof-bars 23.

It will be noted that the improvements heretofore described not only simplify the construction but add to the strength of the structure, at the same time providing means 95 for conducting the heat from the interior of the building to the part outside the building at the junction of the side wall and roof to prevent the formation of ice and the accumulation of snow, as in the Burnham Patent No. 583,247, as well as to provide means for spacing the ends of the roof-bars away from the inside wall of the eave-plate.

I claim:

1. The combination with the framing of 105 a structure, of gusset plates connecting the vertical posts and rafters of said framing, flanges substantially U-shaped in cross-section and disposed at right angles to the plane of said plates, and a combined eave-plate 110 and gutter having the folded portion engaged by said U-shaped flanges and having an inwardly extending raised portion secured to the roofing members of said framing.

2. The combination with the framing of a structure, of gusset plates connecting the vertical posts and rafters of said framing, flanges substantially U-shaped in cross-section and disposed at right angles to the 120 plane of said plates and a combined eave-plate and gutter having its folded portion arranged interiorly of said structure and fixedly secured to said flanges and having a raised inwardly extending upper portion secured to the roofing members of said structure and the eave-plate portion disposed in the same plane as the plane of the roof.

3. The combination with the framing of a structure, of gusset plates connecting the 130

vertical posts and rafters of said framing, flanges on said plates, and a combined eave-plate and gutter having its folded portion supported by said flanges and having a 5 raised inward extension secured to the roofing members of said structure.

4. The combination with the framing of a structure, of gusset plates connecting the vertical posts and rafters, flanges on said 10 plates, and a combination eave-plate and gutter having its folded portion supported by said flanges and an inner raised end extending inwardly and in a plane parallel to the plane of the roof and adapted to engage 15 the roof-bars.

5. A combined eave-plate and gutter having two supports for the edge of the roof, one of said supports being in substantially the same plane as that of the glass and 20 serving as a support for the same and for the upper sides of the roof-bars, and the other support being in a plane parallel to that of the first named support, elevated above the gutter portion, and adapted to 25 engage the underside of the roof-bars.

6. A combined eave-plate and gutter having two supports for the edge of the roof, said roof including a series of roof-bars spaced away from the gutter portion, one 30 of said supports being in substantially the same plane as that of the glass and serving as a support for the same and for the upper sides of the roof-bars, and the other support being in a plane parallel to that of the 35 first named support and adapted to engage the under-side of said roof-bars, and means

for securing said roof-bars to the last named support.

7. A combined eave-plate and gutter having two supports for the edge of the roof, 40 said roof including a series of roof-bars spaced away from the gutter portion, one of said supports being in substantially the same plane as that of the glass and serving as a support for the same and for the upper 45 sides of the roof-bars, and the other support being in a plane parallel to that of the first named support and adapted to engage the under-side of said roof-bars, and means for filling the space between the roof-bar and 50 the second support.

8. A combined eave-plate and gutter having two supports for the edge of the roof, said roof including a series of roof-bars bevelled inwardly at their outer ends, one 55 of said supports being in substantially the same plane as that of the glass and serving as a support for the same and for the upper sides of the roof-bars, and the other support being in a plane parallel to that of 60 the first named support and adapted to engage the under-side of said roof-bars.

9. The combination with the framing of a structure, including vertical posts, of a combined eave-plate and gutter having its folded portion arranged interiorly of said structure, and having a raised inwardly extending upper portion secured to the roofing members of said structure, and supporting 65 means connecting the said eave-plate and gutter to the vertical posts of the framing. 70
